 TERMINAL CONNECTION FOR ELECTRON
DISCHARGE DEVICE

Johannes Antonius Bernardus Dechering, Emmasingel, Eindhoven, Netherlands, assignor to North American Philips Company, Inc., New York, N.Y., a corporation of Delaware

Filed Feb. 1, 1962, Ser. No. 171,329

Claims priority, application Netherlands, Feb. 7, 1961, 260,920

3 Claims. (Cl. 315—3.5)

The invention relates to a device for connecting the cylindrical edge of a disc-shaped electrode lead of an electric discharge tube to a conductive wall, in which in this conductive wall a helically wound spring closed to a torus is provided in a circular recess having a rectangular cross-section, which spring is in contact with the upper and lower sides of the recess as viewed when the tube is mounted vertically and joins the cylindrical edge of the electrode supply.

Contact springs as indicated above are used in many constructions and sometimes the recess has a rounded or trapezoidal cross-section. Although the contact spring is comparatively resilient, so that on inserting the disc-shaped electrode lead no difficulties are experienced, the tolerance at the electrode supply is comparatively small. In electric discharge tubes which comprise a number of disc-shaped electrode leads which in general may show mutual mounting deviations, or in tubes which must, for example, be capable of being adjusted in a magnetic field, the small tolerance sometimes is a drawback. The object of the invention is to mitigate this drawback.

In a device for connecting the cylindrical edge of a disc-shaped electrode supply to a conductive wall, in which in this conductive wall a helically wound spring closed to a torus is provided in a circular recess having a rectangular cross-section, which spring is in contact with the upper and lower sides of the recess and encloses the edge of the electrode lead, the torus-shaped spring is enclosed, according to the invention in a rigid ring which is movable in a radial direction in the circular recess.

With the construction according to the invention, a rather large radial tolerance of the torus-shaped spring can be obtained without the high frequency contact being harmfully influenced by it, because this is ensured by the contact which is made by the turns of the spring with the upper and lower sides of the circular recess, while the spring omni-directionally still encloses the edge.

The invention is of importance for travelling wave tubes, disc-triodes and for klystrons having one, two or more resonators.

In order that the invention may readily be carried into effect, one embodiment thereof will now be described, by way of example, with reference to the accompanying drawing, in which:

FIGURE 1 is a longitudinal sectional view through a travelling wave tube which is mounted in an amplifier device which is provided with one single contact spring mounting according to the invention, while

FIGURE 2 shows a detail of the contact spring mounting according to the invention.

In the figures, reference numeral 1 is the hollow input wave guide and reference numeral 2 the hollow output wave guide of an amplifier having a travelling wave tube 3. Input and output wave guides are connected by a circular-cylindrical wave guide 4, within which the glass wall 5 of the travelling wave guide is located at a small distance. Two metal disc-shaped electrode leads 6 and 7 respectively, which form the connection with the wave

2

guides 1 and 2, respectively are sealed to the wall 5. To the other side of the disc 6, a short glass cylinder 8 is sealed within which the parts of the electron gun not shown are located. The disc 7 supports the collector electrode not shown via a short glass cylinder. Between the discs 6 and 7, the helical delay line 9 is arranged ending in transition members, which line is supported by three ceramic rods 10. A third metal disc-shaped electrode lead 11, which is in contact with the transition of the wave guides 2 and 4 in which a satisfactory tight high-frequency connection is ensured, is passed through the wall in the proximity of the disc 7. The disc 11 supports the satisfactorily conductive tube 12. The cylindrical edge of the disc is indicated by 21.

15 The discs 6 and 7 respectively are in contact with the outer walls of the wave guides 1 and 2 by means of the torus-shaped springs 14 and 15 respectively which are enclosed in the rectangular bored recesses 16 and 17. This is a known construction. However, the edge 21 is 20 in contact with the wall 13 of the wave guide 2 via the torus-shaped spring 18 (FIGURE 2) which is enclosed in the recess 19, which is bored to a wider extent, and in the movable ring 20. The turns of the spring 18 contact the upper and lower sides of the recesses 22 and 23 respectively. 25 As a result of the movability of the ring 20 and the spring 18 enclosed in it, mounting deviations of the disc 11 with respect to the discs 6 and 7 can be prevented.

While the invention has been described in connection with a specific embodiment and applications thereof, other modifications will be apparent to those skilled in the art without departing from the spirit and scope of the invention as defined in the appended claims.

What is claimed is:

1. A terminal connection for connecting a disc-shaped electrode lead with a cylindrical edge of an electron discharge device to a conductive wall provided with a circular recess having a rectangular cross-section, said terminal connection comprising a torus-shaped helically wound spring in contact with the upper and lower sides of the recess and which encloses the edge of the electrode lead, and a rigid annular member movable in a radial direction in the circular recess enclosing the torus-shaped spring.

2. In a travelling-wave tube system including an electron discharge tube having an elongated envelope, a helical delay line within said envelope, terminal members at both ends of said delay line, and input and output wave-guide means each having a conductive wall provided with a circular recess having a rectangular cross-section, the combination of a disc-shaped electrode lead having a cylindrical edge extending through the envelope and connected to a terminal member and a torus-shaped helically-wound spring enclosed in a rigid ring movable in a radial direction in the circular recess of each conductive wall and engaging the upper and lower sides of the recess and the cylindrical edge of the electrode lead.

3. A travelling-wave tube as claimed in claim 2 in which the delay line is surrounded for part of its length by a conductive tube which is connected to one wall of the output wave-guide by a torus-shaped spring and a disc-shaped electrode lead as claimed in claim 2.
